UNITED STATES PATENT OFFICE.

GEORGE W. HADDEN, OF KANSAS CITY, MISSOURI.

WALL-MOLDING APPARATUS.

1,162,913.

Specification of Letters Patent.

Patented Dec. 7, 1915.

Application filed September 22, 1914. Serial No. 862,885.

To all whom it may concern:

Be it known that I, GEORGE W. HADDEN, a citizen of the United States, residing at Kansas City, in the county of Jackson and 5 State of Missouri, have invented certain new and useful Improvements in Wall-Molding Apparatus, of which the following is a full, clear, and exact description, such as will enable others skilled in the art to which 10 it appertains to make and use the same.

The invention relates to lifting jacks for wall forms and seeks to provide a simple and efficient form of lifting jack which may be secured to the wall form and lifted simultaneously with the form as the form is raised after the completion of additional layer of 15 wall.

Walls are constructed by setting forms and filling them with concrete and other material, raising the form for each additional layer after the completion of the one in the form. It is essential that lifting jacks for 20 wall forms be constructed light of weight owing to the necessity of transportation 25 from place to place and to the height to which they must be carried to complete the wall, and also that they may easily and quickly lift the form from the finished section of the wall to that which is to be built.

30 The present invention seeks to provide an improved lifting jack which is directly mounted on the form, is light of weight and may easily be carried to extreme heights as the wall is built and as easily lowered 35 to the ground after the wall is completed, together with a powerful leverage to promote ease in lifting the form, and an automatic gripping means whereby the jack and form is lifted from successive grips and the 40 reinforcing rod which is allowed to remain in the wall.

With these and other objects in view, the invention consists in the features of construction, combinations and arrangements of 45 the parts hereinafter set forth, illustrated in the accompanying drawings and more particularly pointed out in the appended claims.

In the drawings: Figure 1 is a view in 50 elevation of the improved jack connected to a form and illustrating a fragmentary section of wall to show the application. Fig. 2 is a plan view of the jack and a fragment of wall upon which the jack and form are mounted. Fig. 3 is a view in section of certain parts of the operating mechanism taken 55 on line $a-a$ of Fig. 1. Fig. 4 is a fragmen-

tary view illustrating the means that grip the reinforcing rod.

The forms 1 and 2 are of usual construction and as shown are circular horizontally, 60 such as are used for the construction of large grain tanks and the like. It is obvious however that other forms may be used and it is not desired to confine the invention to the uses of circular forms. 65

To the forms 1 and 2 are secured posts 3 in any convenient manner, the means of connection being no part of the invention, the posts having secured to the upper end thereof the longitudinal members 4 and cross member 5 which serve as a means of fixing the upper end of the posts in relative position, and also as a means of securing the lifting members of the jack to the posts. Cross members 6 are secured to longitudinal members 4 and have pivoted to their centers at 7 the upper ends of the toggle joint legs 8 and 9 which are preferably formed in channel shape, while to the lower end of the legs 8 and 9 at 12 and 13 respectively are 70 pivoted the upper ends of the toggle legs 10 and 11 respectively, the lower ends of the latter legs being pivoted at 14 to the collar 23. 75

A suitable member is pivoted between the 80 legs 9 and 11 at 13 comprising three bearing boxes 15, the outer boxes carry one end of the screw threaded shafts 16 with pinions 17 secured on the outer ends thereof, collars 18 being secured to the shafts adjacent the 85 inner ends of the bearings while the center bearing carries a short shaft 19 to the outer end of which is secured the boss 20 of the hand wheel 21, the inner end of the shaft 19 being held from endwise movement by 90 collar 20. A suitable member comprising two screw threaded bearing boxes 22 is pivoted between the legs 8 and 10 at 12, the 95 shafts 16 being screw threaded and resting therein and engaging with the boxes so that as the screws are turned the boxes 22 and 15 may draw closer together or spread 100 farther apart.

A suitable member 23 is pivoted between the legs 10 and the legs 12 and pivoted at 105 14, a vertical hole in the center of the member forming a ring so that it will pass over the reinforcing rod 24 and engage with the clamping jaws 25, the upper side of this ring being smaller internally than the lower 110 inside and tapering on the inside thereof, this taper corresponding to the taper of

the jaws 25. The jaws 25 are constructed round horizontally, the lower end 29 thereof being larger in circumference than the upper end at 26 and the outside tapering upward to 26, the inside part of the jaws having teeth cut therein so that they may grip a rod when forced against it. The outside end of the jaws enlarge in diameter upwardly from the point 26 and being of a shorter length, the inside is also shaped to turn outwardly so that when the ring 23 is drawn up against the upper ends of the jaws the lower ends thereof will turn outward, thereby releasing their grip on the rod 24 as shown in dotted lines in Fig. 1.

To the hand wheel 21 is secured an internal gear 28 preferably formed integral therewith, the gears 17 secured on the ends of the shafts 16 engaging with the internal gear 28. When the hand wheel 21 is turned in one direction the pivots 12 and 13 are spread apart by means of the gears and screw shafts 16 engaging with the threaded bearing boxes 22, thereby causing the pivot end 14 to rise, the ring 23 releasing the jaws 25 and raising said jaws to a higher position, then by turning the hand wheel in the opposite direction the ring 23 will press downwardly on the jaws and grip the rod 24, by a further movement the pivot end 7 will rise causing the posts 3 and form 1 to rise to the desired height so that another portion of the wall may be formed.

The rods 30 hold the forms 1 and 2 to the wall that has been previously molded and prevent them from spreading and are used to grip the forms on a section of wall that is finished while the jaws 29 are being raised to a new position on the rod 24.

40 I claim,

1. In a wall molding apparatus, a frame, a wall form secured to said frame, said frame projecting upward from said form,

members holding the upper end of said frame in relative position, upper toggle 45 joint legs pivoted to and depending from said members, lower toggle joint legs pivoted to said upper legs, a ring pivoted to said lower toggle joint legs, gripping jaws in said ring, and means to spread and retract said 50 toggle joint legs whereby said jaws are raised and lowered, being forced to grip a reinforcing rod in their downward movement and released from said rod in their upward movement, said frame and said form being 55 lifted upon further retraction of said legs.

2. In a wall molding apparatus the combination of a form, a frame rising from said form, toggle joint legs pivoted to and depending within said frame, screws mounted in members pivoted to said legs, means to turn said screws in unison whereby the lower end of said legs are raised and lowered, a ring pivoted to the lower end of said legs and a set of jaws in said ring constructed to grip a rod positioned within said frame whereby said frame and said form are raised as said legs are retracted and said jaws released from said rod while said legs are being spread.

3. In a wall molding apparatus the combination of, a form, a frame rising from said form, toggle joint legs pivoted to said frame, toggle joint legs pivoted to said first mentioned toggle joint legs, means connected to the bottom of said last mentioned toggle joint legs to grip and release a reinforcing rod and means to expand and retract said toggle joint legs whereby said form may be raised.

In testimony whereof I affix my signature in the presence of two witnesses.

GEORGE W. HADDEN.
